DYE SWAB AND COMB COMBINATION

Lee B. Rever, New York, N. Y., assignor to Rapidol Distributing Corp., New York, N. Y., a corporation of New Jersey

Application February 19, 1934, Serial No. 712,022

1 Claim. (Cl. 132—12)

This invention relates to a combination dye swab and comb.

One of the objects of my invention is the provision of a novel combination of the character mentioned, which is simple in construction and efficient in action and in which a dye swab which has been used may be readily replaced with a new one.

Other objects will be appreciated from a reading of the following specification.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therein as do not affect the spirit of the invention nor exceed the scope thereof as expressed in the appended claim.

In the drawing:

Fig. 1 is a side view of the combination dye swab and comb, the handle being fragmentarily shown.

Fig. 2 is an elevational view of the distal end of the device shown in Fig. 1; and

Fig. 3 is a perspective view of the swab used in connection with the comb.

Referring to the drawing for a more detailed description thereof, the numeral 5 indicates a comb provided with a handle 6 extending from a back 7, from which extend teeth 8. The distal end portion of the back of the comb is provided with a slot 9 to form a tongue 10 around which may be positioned a dye swab 11 of porous material, which has a central opening 12 lengthwise therethru, as clearly indicated in Fig. 3, the swab thus being adjacent the teeth so that dye may be applied to the hair as the comb is drawn thru the same. It will readily be appreciated that the construction of my invention provides a simple and efficient device in which one swab may readily be replaced by another.

What is claimed as new is:

In combination, a comb including a back, a series of teeth extending from said back, the latter having a slot extending longitudinally from one end to form a tongue between the rear edge of said back and one side of the slot, and a tubular dye swab around said tongue.
